US00D902054S

(12) **United States Design Patent** (10) Patent No.: **US D902,054 S**
(45) Date of Patent: **** Nov. 17, 2020**

(54) **PACKAGING**

(71) Applicant: **JUUL Labs, Inc.**, San Francisco, CA (US)

(72) Inventors: **Rajeev Bhalla**, Palo Alto, CA (US); **Jason Curtis**, Alameda, CA (US); **Peter C. De Alva**, Lake Zurich, IL (US); **PyiPhyo Lwin**, Newark, CA (US); **James Monsees**, San Francisco, CA (US); **Kevin J. Myers**, San Jose, CA (US); **Vincent C. Phua**, Piedmont, CA (US); **Jambunathan Vangal Ramamurthy**, San Jose, CA (US); **Alexandra N. Siano**, San Francisco, CA (US); **Srinivasan Sundararajan**, Cupertino, CA (US); **Bryan White**, Pleasanton, CA (US); **Thomas J. White**, Pebble Beach, CA (US)

(73) Assignee: **JUUL Labs, Inc.**, San Francisco, CA (US)

(**) Term: **15 Years**

(21) Appl. No.: **29/677,362**

(22) Filed: **Jan. 18, 2019**

(51) LOC (12) Cl. **09-01**

(52) U.S. Cl. **D9/732**

(57)

CLAIM

The ornamental design for a packaging, as shown and described.

DESCRIPTION

FIG. 1 is a bottom, front, and right side perspective view of a packaging of our design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

(Continued)

The long dash-dash broken lines illustrate the appearance of perforations and form a part of the claimed design.

1 Claim, 5 Drawing Sheets
